UNITED STATES PATENT OFFICE.

FRANK GUYVER BRITTON, OF YOKOHAMA, JAPAN, ASSIGNOR TO BABCOCK & WILCOX COMPANY, OF BAYONNE, NEW JERSEY, A CORPORATION OF NEW JERSEY.

CHAIN-GRADE STOKER.

1,192,850.

Specification of Letters Patent.

Patented Aug. 1, 1916.

Application filed December 16, 1914. Serial No. 877,482.

To all whom it may concern:

Be it known that I, FRANK GUYVER BRITTON, a subject of the King of the United Kingdom of Great Britain and Ireland, and residing at No. 1 Isogo Machi, Yokohama, Japan, have invented a certain new and useful Improvement in Chain-Grade Stokers, of which the following is a specification.

10 The subject of this invention is a central feed fuel distributing chain grate stoker for land and marine boilers, comprising an endless traveling chain grate composed of connected links formed as grate bars and side 15 grates composed of fire bars arranged at each side of the said chain grate.

Among the objects of the invention are saving of labor, economy of fuel, uniformity of feed under automatic conditions, and 20 perfection of combustion.

In the accompanying drawings, Figure 1 is a part side elevation part longitudinal section showing the improved stoker fitted to an internally fired boiler such as a boiler 25 of the Lancashire or the Cornish type. Fig. 2 is a section on the line A—A, Fig. 1, the side grates being curved. Fig. 3 is a plan showing the relation of the chain grate and the side grates with fittings, plane side 30 grates having been substituted for the curved grates shown in Fig. 2. Fig. 4 is a side elevation of part of the chain grate. Fig. 5 is a longitudinal section showing the relative position of the hopper and the chain 35 grate. Fig. 6 shows alternative constructions of side grates. Fig. 7 is an end view showing the grates supporting the fuel.

Referring to the drawings, the stoker comprises an endless traveling chain grate 40 disposed centrally of the flue and occupying about one third of the width of the fire bed, and stationary, *i. e.*, non-traveling, grates, one on each side of the chain grate, including the necessary fittings and attachments hereinafter referred to.

The chain grate is led around sprocket 45 wheels 4 at the front end and the drum 5 at the rear end of the fire bed. The sprocket wheel shaft 7 and the drum shaft 6 are fitted in bearing bushes 16 at the front and rear ends respectively of the stoker frame, the top of which frame is parallel to the center line of the flue; the bearings being so located that the upper run of the chain grate 55 is at a lower level than the top of the side

grates at the front end, and is at the same level as the top of the side grates at the rear end, the forward end of the upper run of the chain grate being therefore upwardly inclined in the direction of travel.

The stoker frame comprises members 1 located one on each side of the chain grate, and firmly secured by stays 3.

The side grates are constituted by fire bars 14, which are provided with suitable air passages and are supported by bearers 21 at one end and at the other end by the members 1 of the stoker frame. The fire bars 14 of the side grates may be curved or plane, and set either inclined or horizontal, 70 curved fire bars being illustrated in Fig. 2 and plane fire bars being illustrated in Fig. 3.

The fire bars may be fixed (14^B) or movable (14^A) (Fig. 6) depending on the type of boiler to which the grate is fitted and the kind of fuel to be used. The fire bars 14^A are adapted to be tilted so as to dislodge ash by being lifted at one end by means of rotating cams 25 or the like disposed beneath the same.

8 denotes a fuel hopper located at the front end of the boiler and mounted on the top of the frame 1, the bottom of the hopper being of a width equal to that of the chain grate or to the internal width of the frame 85 1; 9 denotes a fuel regulating door fitted within the hopper, and 10 a hinged flap door resting on the upper surface of the chain grate adjacent to the front end thereof and serving to prevent excess air from 90 entering the furnace.

It will be seen that fuel from the hopper falls on to the chain grate at about the lowest point of the upper run, and travels upward with the chain grate to a point where 95 the latter is at about the level of the inner edges of the side grates, at about which point the surplus fuel falls over on to the side grates until the entire fire bed is completely covered with fuel. The fuel is 100 burned completely at the rear end of the furnace, the ashes being parted and spread on to the side grates at the rear end of the furnace by a wedge-shaped or tapered bridge 13. The ashes formed on the side grates 105 may be raked out through the doors 17 provided in the flue cover plate 18 beneath the hopper 8. Should the chain grate be rendered inoperative owing to mechanical troubles, the doors 17 may be opened to per- 110

mit hand firing to be resorted to. The fuel on the side grates remains stationary and is added to continuously from the central chain grate, the burning fuel on the side grates quickly igniting the incoming green fuel on the central chain grate; that is, in effect, a tunnel of burning fuel is formed under which the incoming fuel completes its combustion by the time it arrives at the rear end of the furnace, so that smoke evolved from the incoming fuel is consumed on its way to the chimney flue. By the time the uppermost layer of fuel is consumed a supply of fresh fuel from beneath is scattered on to the side grates, the tunnel being thus maintained.

Motion is transmitted to the chain grate through a gear box 26 (Fig. 1) fitted at the right or left side of the stoker frame, the transmission mechanism including spur-wheels in the gear box, a worm 23, a worm wheel 15 and a safety friction clutch 24. It will be understood that the speed of movement of the grate (which travels in the direction of the arrow shown in Fig. 5) can be readily varied by changing a set of spur-wheels, and that the friction clutch allows of slip in the event of any obstruction, thus obviating the possibility of injury to the mechanism.

From the foregoing it will be seen that with a chain grate constructed in accordance with the invention the fuel is fed automatically to the fire bed in such manner as to insure an efficient progress of combustion, air being prevented from entering the furnace in excess of that quantity which is required for complete combustion. Thus, the combustion is rendered perfect and the formation of smoke prevented, while the evaporative capacity of the boiler is increased and the fuel consumption diminished. It may also be added that as with the arrangement described complete combustion can be obtained even with rapid firing, the invention is applicable with advantage to boilers of the flash type as well as such for meeting greatly fluctuating demands of steam.

I claim:

1. In a furnace, in combination, two side grates, each grate extending laterally from

one of two spaced substantially vertical walls disposed centrally of the furnace, and an endless traveling chain-grate intermediate said vertical walls, the forward portion of the upper-run of said endless grate being inclined upwardly in the direction of travel from below the top of said vertical walls. 55

2. In a furnace, in combination, side grates disposed centrally of the furnace and an endless traveling chain grate arranged between said side grates, the forward portion of the upper run of said endless grate being inclined upwardly in the direction of travel, the front end of said upper run being 60 located below the level of the top of said side grates, and the rear end of said upper run being approximately at the level of the top of said side grates. 65

3. In a furnace, in combination, spaced side grates disposed centrally of the furnace, supports on the outer and inner sides of said side grates, the inner supports being substantially vertical walls, an endless traveling chain grate arranged intermediate said vertical walls, and having its upper run inclined upwardly in the direction of travel from below the top of said vertical walls and thereby adapted to carry upward a charge 75 of fuel supported laterally by said vertical walls, to a point above the latter, whereby the fuel is caused to fall onto said side grates. 80

4. In a furnace, in combination, an endless traveling chain grate, the forward portion of the upper run of which is inclined upwardly in the direction of travel, rocking supports on either side of said chain grate, and fire bars disposed at an inclination to the horizontal and resting on said supports. 85

5. In a furnace, in combination, side grates, an endless traveling chain grate arranged between said side grates, and a tapering bridge member arranged adjacent to the rear end of the furnace and serving to spread the ashes toward said side grates. 90

In testimony whereof I have signed my name to this specification in the presence of two subscribing witnesses.

FRANK GUYVER BRITTON.
